UNITED STATES PATENT OFFICE.

LEE JACKSON DENNIS, OF MEMPHIS, TENNESSEE.

GRAIN-DRIER.

1,084,732.

Specification of Letters Patent. Patented Jan. 20, 1914.

Application filed May 28, 1912. Serial No. 700,341.

To all whom it may concern:

Be it known that I, LEE J. DENNIS, a citizen of the United States, residing at Memphis, in the State of Tennessee, have invented certain new and useful Improvements in Grain-Driers, of which the following is a specification.

This invention relates to improvements in grain driers and one object of the invention is to dispose the heating pipes and deflecting plates inside the drier in such a manner that the grain will be given a zig-zag path downward in very thin streams; and a further object is to remove the moisture given out by the grain, not only along the sides of the apparatus, but also simultaneously from the middle thereof.

In the accompanying drawing illustrating one embodiment of my invention, Figure 1, shows an end elevation of the drier proper partly in section and with the lower cover plate removed; Fig. 2, is a cross section thereof along lines 2—2 of Fig. 4. Fig. 3 is a side elevation with the side plate partly removed in the left half of the figure; and the right half of the figure is a section on line 3—3 of Fig. 2; Fig. 4 is a top plan view; Fig. 5 is a plan view of the drier with the top removed.

The drier is made up of sections of pipe 10, ordinary gas pipe being suitable, the ends of which are connected by return bends 11, so as to form continuous coils with inlet 12 and exhaust 13, steam being the heating element. The drier may have any number of these coils, eight layers being shown in the illustrations, which are supported by the end plates 14 and a rectangular frame work 15, preferably constructed of angle and 40 channel irons of suitable size. In order to prevent all leakage of the steam inside this frame work, all bends and joints of the pipes are located outside the end plates 14, which arrangement also makes repairs convenient. The pipes do not fit tightly in the end plates and therefore permit moisture to escape around them.

The rows of pipes are staggered, so that an upper row will cover the space between 50 the pipes in the nearest row below. Along the sides of the frame work are positioned a series of deflection plates 16 which slightly overlap each other. These plates serve the double purpose of throwing the falling grain inward, back on the pipes, and of leading the moisture, drawn from the grain,

out from the inner part of the apparatus. To collect this moisture an outer casing 17 is built around the frame work. The end plates of this casing are bolted on so as to be 60 removable in order to facilitate the repair of the pipe joints. An air space about 3 inches wide is formed all around the frame work by this outer casing, into which the moisture escapes.

To remove the moisture from the middle of the apparatus are provided a couple of inverted V-shaped troughs 18, which each are hung over three of the pipes 10 and extend the whole length of the machine. The 70 angular part of the trough is rounded and fits snugly over one of the central pipes. A triangular opening 19 is cut in the end of the plates 14 at each end of the troughs 18, so that all moisture collected under the 75 troughs will be led out to the vent or air space at the ends of the drier. This is one of the essential features of the invention, causing a more perfect and quicker drying than ordinarily would be the case, as without these invented V-shaped troughs or moisture collectors the moisture exuding from the grain in the middle of the machine, would have to find its way through the mass of grain lying on both sides; before it would 85 pass out between the deflectors 16 into the vent.

The V-shaped troughs 18 also serve as central deflectors for the grain falling thereon.

The vents are closed at the top by collecting drums 20 which are inclined upward toward one end of the drier, where they are joined into one and connect with the stack 21. The natural draft through the vents, drums and the stack is sufficient to carry away the 95 moisture. Any dripping of condensed moisture is collected in the bottom of the stack and removed.

A receiving hopper 22 filled from above is situated at the top of the drier. A net 23 100 is stretched across it for collecting husks of straw which may then be removed through the door 24.

The bottom of the drying chamber is made up of three cut off slides 25 running in suitable guides. These slides cover the entrance of the drawing off hopper 26 which extends the whole length of the drier. At the lower end of this hopper is placed a corrugated feed roll 27 and a gate 28. This gate is held 110 down by means of a number of weights 29, and from the adjustment of the weights and

the speed of the feed roll, the speed of drawing off the grain is regulated. Beneath the drawing off hopper 26 is placed a transfer chute 30 for transferring the grain.

5 If a number of driers are used, one steam supply pipe may be used for all, tapping it at each inlet to the driers. Similarly one exhaust pipe may connect all the exhausts.

The method of operation is as follows:

10 After closing the bottom slides 25 and admitting the steam into the pipe coils 10 so that they are well heated, the grain is poured in at the top of the hopper 22 until the drier is filled. On passing downward, the grain 15 is first intercepted by the net 23, which collects all the husks, cobs, sticks or straw that might be mixed with the grain. Farther down the descending grains will be thrown to right and left as they strike the intervening pipes, deflecting plates, or the sides of the troughs, so that the grain will run down in thin, zig-zag streams of not more than $1\frac{1}{2}$ inch thickness. When the grain has been thoroughly heated so that the moisture from 20 the grain is carried away through the openings between the deflectors 16, around the pipes in the end plates 14 and the end openings 19 of the inverted troughs 18, and transferred by way of the drums 20 to the 25 stack 21; the bottom slides 25 are opened admitting the hot grain into the hopper. By proper adjustment of the weights 29 on the gate 28 and the speed of the roll 27 a continuous stream of steaming hot corn will 30 then be drawn off.

As the device is of comparatively small dimension, it may equally well be set up inside or outside a building.

When the device is working continuously, 40 that is, when the receiving hopper 22 is kept filled, no heat will escape through the top of the hopper, as it will all be taken up by the closely packed grain therein. And the grain will not be sufficiently heated to exude 45 any moisture until it has reached the pipes in the heating chamber, through which it proceeds in thin streams downward and every single grain comes in contact with the hot pipes.

50 The inventor, although having described the device for drying grain, does not thereby limit the use thereof to grain only, as the invention is equally well applicable for drying all kinds of cereals as well as flour, salt, 55 sugar and any other substance of similar character.

I claim:

1. In a grain drying device having a heating chamber, a stack for said chamber, said 60 chamber having double walls forming vents all around the chamber, the inner walls of the chamber being provided with a plurality of openings to said vents, downwardly inclined deflecting plates on the inside of said 65 inner walls, partly covering said openings

and forming gateways for passing moisture from said chamber to the surrounding vents, drums forming the top of said vents and inclined so as to carry the moisture from the vents to the stack.

2. In a grain drying device having a heating chamber provided with double walls forming vents all around the chamber, the inner walls of the chamber having a plurality of openings to said vents, downwardly inclined deflecting plates on the inside of said inner walls partly covering said openings and forming gateways between said chamber and the surrounding vents; inverted V-shaped troughs running parallel and connecting the two end walls of said chamber and situated in the central part of the chamber; said end walls having triangular openings conforming in shape with the cross section of and registering with said troughs.

3. In a grain drying device having a heating chamber provided with double walls forming vents all around the chamber, the inner walls of the chamber having a plurality of openings to said vents; downwardly inclined deflecting plates on the inside of said inner walls partly covering said openings and forming gateways between said chamber and the surrounding vents, inverted V-shaped troughs running parallel and connecting the two end walls of said chamber and situated in the central part of the chamber; inner walls of the chamber having openings at each end of said troughs, whereby moisture collecting under the troughs will be led out into said vents.

4. In a grain drying device having a heating chamber provided with double walls forming vents all around the chamber, the inner walls of the chamber having a plurality of openings to said vents; downwardly inclined deflecting plates on the inside of said inner walls partly covering said openings and forming gateways between said chamber and the surrounding vents; a plurality of straight pipes within said chamber, bends connecting the ends of the pipes, said bends being situated in said vents, the pipes and the bends forming a continuous duct for the heating medium; said pipes being distributed in a plurality of horizontal layers and offset relative to each other, providing zig-zag positioned obstructions for the falling grain.

5. In a grain drying device having a heating chamber provided with double walls forming vents all around the chamber, the inner walls of the chamber having a plurality of openings to said vents; downwardly inclined deflecting plates on the inside of said inner walls partly covering said openings and forming gateways between said chamber and the surrounding vents; a plurality of straight pipes within said chamber

- ber, bends connecting the ends of the pipes, said bends being situated in said vents, the pipes and the bends forming a continuous duct for the heating medium; said pipes and said deflecting plates being so located in the chamber that they compel the grain entering at the top to take a zig-zag course through the chamber and run in thin streams.
6. In a grain drying device having a heating chamber provided with double walls forming vents all around the chamber, the inner walls of the chamber having a plurality of openings to said vents; downwardly inclined deflecting plates on the inside of said inner walls partly covering said openings and forming gateways between said chamber and the surrounding vents, a plurality of straight pipes within said chamber, bends connecting the ends of the pipes; said bends being situated in said vents, the pipes and the bends forming a continuous duct for the heating medium; said pipes and said deflecting plates being so disposed that the axes of any three adjoining pipes are situated in the points of an equilateral triangle; inverted V-shaped troughs carried on the adjoining pipes and adapted to form conductors for moisture from the central part of the chamber to the vents.
7. In a grain drying device having a heat-

ing chamber provided with double walls forming vents all around the chamber, the inner walls of the chamber having a plurality of openings to said vents; downwardly inclined deflecting plates on the inside of said inner walls partly covering said openings and forming gateways between said chamber and the surrounding vents; a plurality of straight pipes within said chamber, bends connecting the ends of the pipes; said bends being situated in said vents, the pipes and the bends forming a continuous duct for the heating medium; said pipes and said deflecting plates being so disposed that the axes of any three adjoining pipes are situated in the points of an equilateral triangle; inverted V-shaped troughs carried on the adjoining pipes and adapted to form conductors for moisture from the central part of the chamber to the vents.

The foregoing specification signed at Memphis, Tenn., this third day of May 1912.

LEE JACKSON DENNIS.
